UNITED STATES PATENT OFFICE.

RICHARD F. GILE, OF CLIFTONDALE, MASSACHUSETTS, ASSIGNOR, BY MESNE ASSIGNMENTS, TO GEORGE K. WOODWORTH, TRUSTEE, OF BROOKLINE, MASSACHUSETTS.

INTERNAL-COMBUSTION ENGINE.

1,235,325.

Specification of Letters Patent. Patented Mar. 30, 1920.

Application filed May 9, 1916. Serial No. 96,423.

To all whom it may concern:

Be it known that I, RICHARD F. GILE, a citizen of the United States, and a resident of Clifftondale, in the county of Essex and State of Massachusetts, have invented a new and useful Improvement in Internal-Combustion Engines, of which the following is a specification.

My invention relates to internal combustion engines and more especially to engines of the combined pump and motor cylinder type, either single or double acting, and its object is to provide a simple and efficient means connected directly to the power-piston connecting-rod or pitman for controlling the motion of the sub-piston.

The drawings which accompany and form a part of this specification show an illustrative embodiment of my invention, but it is to be understood that the construction herein particularly described may be widely varied without departing from the scope of my invention as defined by the appended claims.

25 In the drawings—

Figure 1 is a central longitudinal section of the frame and cylinder of a single acting engine embodying my improved sub-piston control, the moving members being shown 30 in elevation as they would appear looking toward the left from a plane passing through the line X—X of Fig. 2 normal to the axis of the crank-shaft. Fig. 2 is a longitudinal section taken on the line 2—2 35 of Fig. 1. Figs. 3, 4, 5 and 6 are diagrams showing the positions of the moving parts at various points in the cycle.

In the particular drawings selected for more fully disclosing my invention, 1 represents a frame connected by the bolts 2 to the base 3, the frame and base inclosing the lower portion of the engine.

Suitably secured to the top of the frame is a cylinder 4, the open lower end of which projects into the frame, its upper end being closed by the head 5 attached thereto by the bolts 6 and having a number of fuel passages or flutes 7 arranged lengthwise in its bore and communicating with the combustion chamber A. Any suitable number of flutes, say from 16 to 20, more or less, may be used. A spark-plug 8 is screwed into the cylinder-head, its points projecting into the combustion chamber A, and the cyl-

inder and head are water-jacketed as shown 55 at 9, 10.

Arranged to reciprocate within the cylinder is a power piston 11, herein shown as a trunk piston, and a double pitman 12 engages the pin 13 secured in the walls 60 thereof and connects said piston to the wrist pin 14 of the crank 15 to transmit power developed in the cylinder to the main crank-shaft 16 journaled in the bearings 17 integral with the engine frame and 65 base. A sub-piston 18 is arranged to reciprocate within the cylinder between the power piston and the combustion chamber and its rod 19 passes through and is guided by a longitudinal bore in the central core 70 of the power piston, its lower end being pivotally connected to one end of the link 20, the other end of which engages the centrally-arranged arm 21 of the hollow rock-shaft 22, arranged to oscillate about the stationary shaft 23, which is secured in the bosses 23' projecting inwardly from the sides of the frame. Secured to, or, as shown 75 in the present instance, integral with one end of said rock-shaft, is a somewhat shorter 80 arm 24, which by means of the connecting rod 25 is articulated with the arm 27 of the bell-crank 28 pivotally connected to the frame by the pin 29, the pin 26 which projects from said arm 27 to the right, as 85 viewed in Fig. 2, engaging the lower hub of the connecting rod 25. The other arm 30 of said bell-crank is pivotally connected by the link 31 with one member of the double pitman 12, the lower hub of said link engaging the pin 30' which projects from said 90 bell-crank toward the left, as viewed in Fig. 2, and its upper hub engaging the pin 32 fixed into the pitman 12.

The cylinder has an exhaust passage 95 controlled by the inwardly-opening valve 34 normally held to its seat by the spring 35 which surrounds the valve stem and bears against the valve housing and the collar 36 on said stem. The valve may be 100 opened by any suitable mechanism, such for example as the tappet 37 actuated by the cam 38 which cooperates with the head 39 thereof, gearing (not shown) being employed to connect the cam 40 with the crank-shaft.

The fuel inlet 41 is located a short distance above the lower end of the power piston

when the latter is in explosion position at the end of its up-stroke, as shown in Fig. 1, and may be connected to any suitable source of fuel.

5 It will be understood of course that the foregoing detailed description comprises various elements which in the precise form shown in the drawings and described herein are not essential to my invention and that 10 these parts may be considered simply as typical of the necessary elements of an internal combustion engine.

By means of the flutes or fuel passages 7 I secure an intimate and substantially perfect mixture of the fuel charge and this results in practically complete combustion. 15 As the power piston approaches the head of the sub-piston the charge which is contained in the space between these two elements is compressed and forced by such compression around the advancing head of the sub-piston through the restricted passage afforded by the flutes or fuel passages and is shot with great force against the 20 cylinder head in a number of relatively small streams.

An explosion of the compressed charge in the combustion chamber acts directly on the head of the sub-piston and by the latter is 30 communicated to the power piston. It is absolutely necessary that the two pistons shall travel at the same rate of speed without the slightest relative movement until the sub-piston shall have covered the inner 35 ends of the flutes. The reason for this will be obvious from an inspection of Fig. 2 in which the parts are shown in the position occupied immediately prior to ignition in the combustion chamber A. Should the 40 power piston begin to move away from the sub-piston before the latter covers the inner ends of the flutes, a portion of the effect of the explosion will be exerted against the lower face of said sub-piston in opposition 45 to the force exerted on the upper face thereof. It is essential also that the subsequent relative movement between the pistons be created positively.

The positive relative movement of the sub-piston with respect to the power piston is 50 created by the pitman which communicates the necessary motion to the sub-piston through the link 31, bell-crank 28, connecting rod 25, rock-shaft 22, the arms 24 and 21 55 which are rigidly connected to said rock-shaft, and the link 20. The operation of these elements will be explained with reference to Figs. 3, 4, 5 and 6, on which the several moving parts are indicated by lines 60 identified by reference numerals corresponding to those used on Figs. 1 and 2 and provided with exponents I, II, III, etc., to designate the successive positions of said parts.

65 When both pistons are at the upper ends

of their strokes (explosion position) as shown in Figs. 1, 2 and 3 and the charge compressed in the combustion chamber, the valve 34 being closed, the charge is fired and the resulting explosion causes both pistons to descend at the same initial rate of speed and without any relative movement substantially until the crank 15, which rotates in the direction of the arrows, has passed from its initial position 15 (Fig. 3) 70 to a point somewhat less than 135 degrees therefrom or the position at which the link 31 is normal to the pitman 12. At this point the sub-piston has reached the end 75 of its stroke and its face is slightly above the fuel inlet. The sub-piston, just before reaching the end of its stroke, begins to lag and the power piston moves away therefrom. The sub-piston immediately having reached the end of its stroke begins to move 80 upwardly, the power-piston meanwhile continuing its down-stroke to position 11' (Fig. 4.) Fig. 4 shows the position of the parts when the crank has reached the position 15' 85 or 135 degrees from its initial position. The power piston has almost reached the end of 90 its down-stroke and, the link 31, having just commenced to make an angle with the pitman and draw the bell-crank clockwise, the sub-piston has just started upwardly. From 95 the position 15' of the crank to the position 15'', the movement of the sub-piston is extremely rapid, and the relative motion between the two pistons creates a partial vacuum in the space between the same, thereby drawing a charge of fuel thereinto which 100 will be compressed by the up-stroke of the power piston as soon as the latter has covered the fuel inlet. The exhaust valve 34 opens practically simultaneously with or 105 preferably shortly before the commencement of the up-stroke of the sub-piston and the burnt gases of the preceding explosion are mechanically expelled by the latter. As the power piston rises and compresses the gas 110 between the pistons, a portion of such gas passes around the head of the sub-piston through the flutes to the combustion chamber and pneumatically expels the remaining portion of the burnt gas through the exhaust 115 passage whereupon the exhaust valve closes.

As shown by Fig. 5, the sub-piston has arrived at position 18'' which is just below its explosion position when the crank is 180 120 degrees from its initial position and the power piston is at the end of its down-stroke. The power piston now begins to rise, but the sub-piston remains practically stationary until the crank 15 returns to initial position, whereupon both pistons will be found at explosion position. Referring to Fig. 6, three positions 15''', 15^{iv}, 15^v of the main crank between 270 degrees and initial position are shown, and the corre- 130

sponding positions of the arms 27, 30 of the bell-crank, the arms 24, 21 of the rock-shaft, and the upper face of the sub-piston are correspondingly marked. It will be noted that 5 as the crank passes from position 15" to position 15''' the sub-piston recedes very slightly from position 18" to 18''' and that as said crank passes from position 15''' to initial position the sub-piston gradually 10 rises a very short distance to its explosion position arriving again at said position at the instant that the power piston has completed its up-stroke.

The relative movement of the pistons during 15 their up-strokes and after the power piston has covered the fuel inlet, will effect the compression of the charge and drive the same with great force through the flutes into the combustion chamber, thereby shooting 20 the charge against the cylinder head in a plurality of relatively small streams and effecting the thorough mixture of the same until the crank arrives at initial position whereupon ignition occurs and the cycle is 25 repeated, there being one explosion at the end of every up-stroke or one per revolution of the crank-shaft.

It will be obvious that by duplicating the 30 sub-piston control apparatus, my invention may be applied to a double-acting engine having two pistons, one on each side of the power piston.

While I have described in detail the relative movement of the parts which I have 35 found to be satisfactory in practice, it will be understood that I do not limit myself specifically thereto, for said parts may be variously adjusted and timed and other cycles may be effected.

40 I claim:

1. An internal combustion engine comprising a cylinder, a power piston and a sub-piston both arranged to reciprocate within said cylinder, said sub-piston being 45 located between the power piston and the combustion chamber, a crank, a pitman connecting said power piston to said crank, and means connected directly to said pitman intermediate the ends thereof for controlling 50 said sub-piston.

2. An internal combustion engine comprising a cylinder provided with a combustion chamber at one end only, a sub-piston and a power piston both arranged to reciprocate 55 within said cylinder, said sub-piston having a single head located between said combustion chamber and said power piston, a crank, a pitman connecting said power piston to said crank and means connected 60 directly to said pitman intermediate the ends thereof for controlling said sub-piston.

3. An internal combustion engine comprising a cylinder, a power piston and a sub-piston both arranged to reciprocate 65 within said cylinder, a crank, a pitman con-

nnecting said power piston to said crank, and means connected directly to said pitman intermediate the ends thereof for causing positive movement of said pistons at the same initial rate of speed without relative 70 movement and for causing, subsequently, positive relative movement between the same.

4. An internal combustion engine comprising a cylinder, a power piston and a 75 sub-piston both arranged to reciprocate within said cylinder, a crank, a pitman connecting said power piston to said crank and means connected directly to said pitman intermediate the ends thereof for causing 80 positive movement of said pistons initially at the same rate of speed without relative movement and subsequently at different rates of speed.

5. An internal combustion engine comprising a cylinder; a power piston and a sub-piston both arranged to reciprocate within said cylinder, a crank, a pitman connecting said power piston to said crank, and means connected directly to said pitman intermediate the ends thereof for causing said pistons to travel at the same rate of speed without relative movement until the sub-piston reaches the end of its down-stroke and for causing, subsequently, positive relative 95 movement between the same.

6. An internal combustion engine comprising a cylinder, a power piston and a sub-piston both arranged to reciprocate within said cylinder, a crank, a pitman connecting said power piston to said crank and means actuated by said pitman for causing said pistons to travel at the same rate of speed without relative movement until the sub-piston reaches substantially the end of its 105 down-stroke, for causing, subsequently, positive relative movement between the same and for holding the sub-piston substantially stationary at the end of its up-stroke until the power piston completes its up-stroke. 110

7. An internal combustion engine comprising a cylinder, a power piston and an imperforate sub-piston both arranged to reciprocate within said cylinder, a crank, a pitman connecting said power piston to said 115 crank and means actuated by said pitman for causing said pistons to travel at the same rate of speed without relative movement until the sub-piston reaches substantially the end of its down-stroke, for causing, subsequently, positive relative movement between the same, for moving said sub-piston substantially to its explosion position at the end of its up-stroke by the time the power piston has reached the end of its down-stroke and for holding said sub-piston practically stationary until the power piston reaches the end of its up-stroke. 120

8. An internal combustion engine comprising a cylinder, a power piston and an 130

- imperforate sub-piston both arranged to reciprocate within said cylinder, a crank, a pitman connecting said power piston to said crank and means actuated by said pitman for moving said sub-piston from the end of its down stroke substantially to its explosion position by the time the power piston has arrived at the end of its power stroke in the opposite direction.
10. An internal combustion engine comprising a cylinder, a power piston and a sub-piston both arranged to reciprocate within said cylinder, a crank-shaft, a pitman connecting said power piston thereto, a bell-crank pivoted on one side of said crank-shaft, a rock-shaft pivoted on the other side thereof, two arms on said rock-shaft, a link connecting the rod of said sub-piston to one arm of said rock-shaft, a rod connecting the other arm of said rock-shaft to one arm of said bell-crank, and a link connecting the other arm of said bell-crank to said pitman.
15. An internal combustion engine comprising a cylinder, a power piston and a sub-piston both arranged to reciprocate within said cylinder, a crank-shaft, a pitman connecting said power piston thereto, a bell-crank and a rock-shaft both pivoted in proximity to said crank-shaft, two arms on said rock-shaft, a link connecting the rod of said sub-piston to one arm of said rock-shaft, a rod connecting the other arm of said rock-shaft to one arm of said bell-crank, and a link connecting the other arm of said bell-crank to said pitman.
20. An internal combustion engine comprising a cylinder, a power piston and a sub-piston both arranged to reciprocate within said cylinder, a crank-shaft, a pitman connecting said power piston thereto, a bell-crank and a rock-shaft both pivoted in proximity to said crank-shaft, two arms on said rock-shaft, a link connecting the rod of said sub-piston to one arm of said rock-shaft, a rod connecting the other arm of said rock-shaft to one arm of said bell-crank, and a link connecting the other arm of said bell-crank to said pitman.
25. An internal combustion engine comprising a cylinder, a power piston and a sub-piston both arranged to reciprocate within said cylinder, a crank-shaft, a pitman connecting said power piston thereto, a bell-crank and a rock-shaft both pivoted in proximity to said crank-shaft, two arms on said rock-shaft, a link connecting the rod of said sub-piston to one arm of said rock-shaft, a rod connecting the other arm of said rock-shaft to one arm of said bell-crank, and a link connecting the other arm of said bell-crank to said pitman.
30. An internal combustion engine comprising a cylinder, a power piston and a sub-piston both arranged to reciprocate within said cylinder, said sub-piston being located between the power piston and the combustion chamber, a crank-shaft, a pitman connecting said power piston thereto, and connections interposed between a point intermediate the ends of said pitman and the rod of said sub-piston for controlling the motion of the latter.
35. An internal combustion engine comprising a cylinder provided with a combustion chamber at one end only, a sub-piston and a power piston both arranged to reciprocate within said cylinder, said sub-piston having a single head located between said combustion chamber and said power piston, a main shaft having a crank, a pitman connecting said power piston to said crank, means for causing the sub-piston to travel in contact with the power piston during a substantial portion of the power stroke and for causing, subsequently, positive relative movement between said pistons, and a member connecting said means to said pitman.
40. An internal combustion engine comprising a cylinder, a power piston and a sub-piston both arranged to reciprocate within said cylinder, a crank, a pitman connecting said power piston to said crank, and means whereby the charge of fuel in said cylinder is transferred under pressure from the space between said pistons to the combustion chamber in a plurality of relatively small streams.
45. An internal combustion engine comprising a cylinder having a plurality of fuel passages arranged lengthwise in its bore at one end thereof, a power piston and a sub-piston both arranged to reciprocate within said cylinder, a crank, a pitman connecting said power piston to said crank, and means actuated by said pitman for causing positive movement of said pistons at the same initial rate of speed without relative movement and for causing, subsequently, positive relative movement between the same, and means whereby the charge of fuel in said cylinder is transferred under pressure from the space between said pistons to the combustion chamber in a plurality of relatively small streams.
50. An internal combustion engine comprising a cylinder having a plurality of fuel passages arranged lengthwise in its bore at one end thereof, a power piston and a sub-piston both arranged to reciprocate within said cylinder, a crank, a pitman connecting said power piston to said crank, and means actuated by said pitman for causing positive movement of said pistons at the same initial rate of speed without relative movement and for causing, subsequently, positive relative movement between the same.
55. An internal combustion engine comprising a cylinder having a plurality of fuel passages arranged in its bore near one end thereof, said fuel passages communicating with the combustion chamber of the engine, a power piston and a sub-piston both arranged to reciprocate within said cylinder, a crank, a pitman connecting said power piston to said crank and means actuated by said pitman for causing positive movement of said pistons at the same initial rate of speed without relative movement and for causing, subsequently, positive relative movement between the same.
60. An internal combustion engine comprising a cylinder, a power piston and a sub-piston both arranged to reciprocate within said cylinder, a crank, a pitman connecting said power piston to said crank, and means actuated by said pitman for causing positive movement of said pistons at the same initial rate of speed without relative movement and for causing, subsequently, positive relative movement between the same.
65. An internal combustion engine comprising a cylinder, a power piston and a sub-piston both arranged to reciprocate within said cylinder, a crank, a pitman connecting said power piston to said crank, and means actuated by said pitman for causing positive movement of said pistons at the same initial rate of speed without relative movement and for causing, subsequently, positive relative movement between the same.

- prising a cylinder provided with a combustion chamber, a sub-piston and a power piston both arranged to reciprocate within said cylinder, said sub-piston being located between said combustion chamber and said power piston, a main shaft having a crank, a pitman connecting said power piston to said crank, means for causing the sub-piston to travel in contact with the power piston during a substantial portion of the power stroke and for causing, subsequently, positive relative movement between said pistons, and a member connecting said means directly to said pitman intermediate the ends thereof.
19. An internal combustion engine comprising a cylinder, a sub-piston and a power piston both arranged to reciprocate within said cylinder, a main shaft having a crank, a pitman connecting said power piston to said crank, means for causing the sub-piston to travel in contact with the power piston during a substantial portion of the power stroke and for causing, subsequently, positive relative movement between said pistons, and a member connecting said means directly to said pitman intermediate the ends thereof.
20. An internal combustion engine comprising a cylinder, a sub-piston and a power piston both arranged to reciprocate within said cylinder, a main shaft having a crank, a pitman connecting said power piston to said crank, means for causing the sub-piston to travel in contact with the power piston during a substantial portion of the power stroke and for causing, subsequently, positive relative movement between said pistons, and a member connecting said means directly to said pitman intermediate the ends thereof.
- stroke and for causing, subsequently, positive relative movement between said pistons, and a member connecting said means directly to said pitman intermediate the ends thereof.
20. An internal combustion engine comprising a cylinder, a power piston and a sub-piston both arranged to reciprocate within said cylinder and to travel in the same direction during the power stroke, a crank, a pitman connecting said power piston to said crank, means for controlling said sub-piston positively throughout the entire cycle, and a member connecting said means directly to said pitman intermediate the ends thereof.
- In testimony whereof I have hereunto subscribed my name this 22nd day of April, 1916.
